Primary Examiner — Rhea Shields

(57) **CLAIM**

The ornamental design for a power outlet as shown and described.

DESCRIPTION

FIG. 1 is a top front side view of a power outlet showing my new design;

FIG. 2 is a front view of the power outlet;

FIG. 3 is a rear view of the power outlet;

FIG. 4 is a left side view of the power outlet;

FIG. 5 is a right side view of the power outlet;

FIG. 6 is a top view of the power outlet; and,

FIG. 7 is a bottom view of the power outlet.

The broken lines are illustrative of portions of the article forming no part of the claimed design.

1 Claim, 5 Drawing Sheets

FIG. 1

FIG. 2

FIG. 3

FIG. 4

FIG. 5

FIG. 6

FIG. 7
